UNITED STATES PATENT OFFICE.

JOHN Q. C. SEARLE, OF TOPEKA, KANSAS.

IMPROVEMENT IN BASE-BURNING STOVES.

Specification forming part of Letters Patent No. 136,772, dated March 11, 1873.

To all whom it may concern:

Be it known that I, JOHN Q. C. SEARLE, of Topeka, county of Shawnee, State of Kansas, have invented Improvements in Base-Burning Stoves, of which the following is a specification:

The objects of my invention are, first, to prevent the ignition of the fuel in the magazine of a base-burning stove, and to dispose of and utilize the gases as they are generated in the said magazine; second, to provide for a thorough circulation of the heated products of combustion through the stove before they are permitted to pass off; third, to prevent ashes or particles of ignited fuel from dropping through the grate upon the floor when the ash-drawer is removed; and, fourth, a grated fire-pot, composed of parts, any or all of which can be readily detached.

The first of these objects I attain in the manner best observed in Fig. 1. The magazine A communicates freely at the top with a surrounding gas-chamber, B, having no outlet above, and terminating below at a point coinciding with the lower end or mouth of the magazine. The gases, instead of being permitted to accumulate in the magazine, as usual, and thereby induce the ignition of the fuel in the same, are caused to pass over the top of the magazine; thence downward through and out of the mouth a' of the gas-chamber B, at or below the lower end of which they are ignited by the products of combustion rising from the fire-pot, the gases burning freely, owing to the admission of air through an annular opening, a , in an air-chamber, D, the latter surrounding the gas-chamber and magazine, and projecting below the same. The chamber D is supplied with air through openings b in the side of the stove, and the supply may be regulated by adjusting an annular register, c , with which the said air-chamber is provided.

The second object of my invention—the circulation of the heated products of combustion through the stove—is obtained by means of descending flues E forming a communication between the combustion-chamber F and a chamber, G, at the base of the stove, and by ascending flues H, which connect the chamber G with a chamber, I, at the top of the stove, the products of combustion pass-

ing off through a central outlet-flue, J, furnished with a register, d , for checking the draft when necessary. The diving-flues E extend upward into the combustion-chamber to a point considerably above the lower end of the air-chamber D, as shown in Fig. 1, and in the vertical section, Fig. 2; and in order to prevent the products of combustion from passing too directly into the said flues, deflectors K, Figs. 2 and 3, are interposed between the flues and the walls of the air-chamber D, said deflectors directing the products of combustion outward toward the exterior walls of the stove and around the sides of the said flues, as indicated by the arrows. When a direct draft is required, valves $v v$ in the sides of the flues H, within the combustion-chamber, are opened.

The third object of my invention—the prevention of the dropping of ashes or ignited fuel from between the bars of the grate upon the floor when the ash-drawer is removed—is attained by means of a sliding plate, M, Fig. 1, adapted to guides at the bottom of the ash-pit just above the drawer P, so that when the latter is removed the plate may be moved across the opening in the bottom of the ash-pit, and thus serve to catch and retain all falling particles.

The grated fire-pot Q, to improve which is the fourth object of my invention, is composed of a number of independent and separately-detachable vertical bars, f , Figs. 1, 4, 5, and 6, each formed with a hooked upper end, g , by means of which it is suspended from a circular flange, h , of the body of the stove, and each having upon both sides two lugs, i and i' , which maintain the said bars at a proper distance apart from each other, and thus form spaces k between the same for the admission of air from the annular space x surrounding the fire-pot to the mass of ignited fuel contained within the latter. The bars being entirely separate and independent of each other, any or all of them can be readily removed and replaced by new ones, when such renewal becomes necessary in consequence of the burning out or injuring of the said bars.

I claim as my invention—

1. A stove in which the gases generated in the magazine are discharged from a passage,

a', independent of the magazine, among the unignited mass of coal above the surface of the fire.

2. The combination, in a base-burning stove, of the air-chamber D, and an intervening independent gas-chamber, B, all arranged as described.

3. The combination, in a base-burning stove, of a flue or flues, H, connecting chambers at the top and base of the stove, and flues E communicating with the lower chamber and with the combustion-chamber, substantially as described.

4. The deflectors K, interposed between the descending draft-flues E and the walls of the air-chamber D, substantially as and for the purpose specified.

In testimony whereof I have signed my name to this specification in the presence of two subscribing witnesses.

JOHN Q. C. SEARLE.
